[57] CLAIM

The ornamental design for a pump adapter housing, substantially as shown and described.

DESCRIPTION

FIG. 1 is a perspective view of a pump adapter housing showing my new design;

FIG. 2 is an elevational view taken from the end shown in FIG. 1;

FIG. 3 is a top plan view thereof, the bottom being plain and unornamented;

FIG. 4 is an elevational view taken from the side opposite that shown in FIG. 1; and

FIG. 5 is an elevational view taken from the end opposite that shown in FIG. 2.
